M. D. RIKER

LIFTING JACK

Filed Dec. 26, 1918

Inventor
Malcolm D. Riker
By his attorneys
Marshall C. Dearborn

UNITED STATES PATENT OFFICE.

MALCOLM D. RIKER, OF DOVER, NEW JERSEY, ASSIGNOR TO MCKIERNAN-TERRY DRILL COMPANY, A CORPORATION OF NEW JERSEY.

LIFTING JACK.

Application filed December 26, 1918. Serial No. 268,348.

To all whom it may concern:

Be it known that I, MALCOLM D. RIKER, a citizen of the United States of America, and a resident of Dover, county of Morris, 5 and State of New Jersey, have invented certain new and useful Improvements in Lifting Jacks, of which the following is a specification, reference being had to the accompanying drawings, forming a part thereof.

10 This invention relates to new and useful improvements in lifting jacks of the screw type, and its object is to provide a simple, inexpensive and efficient device of this character which is both strong and light.

15 In order that my invention may be thoroughly understood, I will now proceed to describe the same in the following specification, and will then point out the novel features thereof in appended claims.

20 Referring to the drawings:

Figure 1 is a sectional elevation of a jack made according to and embodying this invention, the section being taken on the line 1—1 of Figure 2.

25 Figure 2 is a similar view taken at right angles to the view shown in Figure 1 or on the line 2—2 of the latter figure.

Figure 3 is a sectional plan view on the line 3—3 of Figure 1.

30 Figure 4 is a sectional plan view on the line 4—4 of Figure 1.

Figure 5 is a sectional plan view on the line 5—5 of Figure 1.

35 Like characters of reference designate corresponding parts in all the figures.

40 10 designates a base of cast or forged metal, which has an upstanding integral collar. This, as shown, in Figure 4, is a continuous part composed of two portions 11—11 which are semi-cylindrical and intermediate flat parallel sides 12—12.

An inner shell 13 is welded or otherwise affixed to this base. The inner shell is a cylindrical tube which from diametrically 45 opposite parts 14 to its lower end, is flattened to a cross-section shape corresponding in form with the collar 11, 12 but sufficiently larger to fit over the collar to which it is affixed. The flat parallel sides of the inner shell are designated by the reference numerals 15—15, and its upper cylindrical portion by the reference numeral 16.

50 17 is an outer shell of cylindrical form which fits slidably over the part 16 of the inner shell. Near its lower end it is flat-

tened at 18 to form flat sides 19—19 which fit over the flat parts 15 of the inner shell.

20 20 is the head of the device which is screwed unto the upper end of the outer shell 17 and into its upper end is screwed 60 the engaging plate 21. There is a circular recess in the center of the under side of the engaging plate into which fits the upper reduced end 22 of the lifting screw 23 which is preferably made hollow as shown at 24. 65 The thin walls of the shells permits the use of a lifting screw of comparatively larger diameter, and of consequently greater strength, than is possible with such constructions as have been available heretofore. 70

A worm gear 25 is keyed or otherwise affixed to the lifting screw and a worm 26 which has bearings in the head 20 is in mesh with it. 27 is a thrust member surrounding the end 22 of the lifting screw and interposed between the upper end of the worm gear 25 and the engaging plate 21. 75

20 A stationary nut 28 provided with internal threads with which the lifting screw engages, is fitted in the upper cylindrical part 16 of the inner shell. The lower end of this nut is flattened on opposite sides as at 29 to fit into the flattened part of the inner shell which prevents the nut from turning. 80

When the worm 26 is turned in one direction, the lifting screw is rotated in the nut and raises the head 20 and the parts connected with it. This movement may be continued until the parts 18 of the outer shell 90 come in contact with the parts 14 of the inner shell. This limits the lift of the jack and as these parts 18 and 14 are beveled surfaces they form an effective stop without jamming the metal. 95

The jack herein described is very light for its strength. It is easily constructed of few parts and needs but little machining. The inner and outer shells are made of commercial tubing, pressed into desired shapes. 100 These may be made in quantities, kept in stock and cut off at desired lengths to make jacks of different sizes. The flattened sides of the shells effectively prevents relative rotation. This eliminates one of the objectionable features of worm driven screw jacks and permits the use of a steep pitch of thread on the lifting screw. 105

A structure of preferred form and construction has been illustrated and described 110

for the purpose of showing a way in which this invention may be used, but the inventive thought upon which this application is based is broader than this illustrative embodiment, 5 and I therefore intend no limitations other than those imposed by the appended claims.

What I claim is:

1. A lifting jack comprising two tubular members each having cylindrical portions 10 engaging each other, portions with flattened engaging surfaces, and shoulders between the cylindrical portions and the portions with flattened surfaces, and means for relatively sliding said members, said shoulders 15 being arranged to limit the extent of such relative movement.
2. A lifting jack comprising two tubular members each having cylindrical portions engaging each other, portions with flattened 20 engaging surfaces, and beveled shoulders between the cylindrical portions and the portions with flattened surfaces, and means for relatively sliding said members, said beveled shoulders being arranged to limit the extent 25 of such relative movement.
3. A lifting jack comprising an inner member having a comparatively short upper portion with an external cylindrical surface, and a longer portion having a flat side, 30 an outer member having a comparatively long portion with an internal cylindrical surface fitting the cylindrical portion of the inner member and a shorter portion having a flat side engaging the flat side of the 35 inner member, and means for relatively sliding said members.
4. A lifting jack comprising an inner tubular member having a comparatively short upper portion with an external cylindrical 40 surface, and a longer portion having flattened surfaces, an outer tubular member having a comparatively long portion with an internal cylindrical surface fitting the cylindrical portion of the inner member and a 45 shorter portion having flattened surfaces engaging the flattened surfaces of the inner member, and means for relatively sliding said members.
5. A lifting jack comprising an inner tubular member having a comparatively short upper portion with an external cylindrical surface, and a longer portion having flattened 50 surfaces, an outer tubular member having a comparatively long portion with an internal cylindrical surface fitting the cylindrical portion of the inner member and a shorter portion having flattened surfaces 55 engaging the flattened surfaces of the inner member, means for relatively sliding said members, and a base having a part fitted into and affixed to the lower end of said inner member.
6. A lifting jack comprising two members 60 of commercial tubing having engaging surfaces, parts of the engaging surfaces of both 65

of said members being depressed throughout unlike portions of their lengths to prevent relative rotation of the members, and each member having at the end of its depressed part a shoulder, means for relatively sliding said members, said shoulders being arranged to limit the extent of said relative sliding movement. 70

7. A lifting jack comprising two members of commercial tubing having engaging surfaces, parts of the engaging surfaces of both of said members being depressed throughout unlike portions of their length to prevent relative rotation of the members, and each member having at the end of its depressed part a beveled shoulder, and means for relatively sliding said members, said beveled shoulders being arranged to limit the extent of said relative sliding movement. 75

8. A lifting jack comprising two members of commercial tubing having engaging surfaces, parts of the engaging surfaces of both of said members being depressed throughout unlike portions of their lengths to prevent relative rotation of the members, 80 and each member having at the end of its depressed part a shoulder, rotative means for relatively sliding said members, said shoulders being arranged to limit the extent of said relative sliding movement. 85

9. A lifting jack comprising two members of commercial tubing having engaging surfaces, parts of the engaging surfaces of both of said members being depressed throughout unlike portions of their length 90 to prevent relative rotation of the members, and each member having at the end of its depressed part a beveled shoulder, rotative means for relatively sliding said members, said shoulders being arranged to limit the extent of said relative sliding movement. 95

10. A lifting jack comprising two members of commercial tubing having engaging surfaces, parts of the engaging surfaces of both of said members being depressed throughout unlike portions of their lengths 100 to prevent relative rotation of the members, and each member having at the end of its depressed part a beveled shoulder, said beveled shoulders being arranged to limit the extent of said relative sliding movement. 105

11. A lifting jack comprising telescopically engaged members of standard commercial tubing of initially uniform cross section slidingly fitting one over the other and having interfitting portions in the sides thereof deformed out of the uniform outline of the tubing for parts of the 110

lengths of such members to prevent relative rotation of the members and to provide stop shoulders at the commencement of such deformed portions engaging to limit the 5 sliding movement of one member over the other and means for relatively sliding the members.

12. A lifting jack comprising an inner member having a longitudinally short portion with an external circumferentially continuous cylindrical surface and a longitudinally longer portion with a flat side;

an outer member having a longitudinally long portion with an internal circumferentially continuous cylindrical surface with 15 which the cylindrical portion of the inner member forms a sliding fit, and a longitudinally shorter portion with a flat side forming a sliding engagement with the long flat side of the inner member, and means 20 for relatively sliding said members.

In witness whereof, I have hereunto set my hand this 21 day of December, 1918.

MALCOLM D. RIKER.
